UNITED STATES PATENT OFFICE.

FRANKLIN E. CRAWFORD, OF WINCHESTER, MASSACHUSETTS, ASSIGNOR TO BANKERS ELECTRIC PROTECTIVE ASSOCIATION, OF BOSTON, MASSACHUSETTS, A CORPORATION OF MASSACHUSETTS.

TIME-CLOCK INDICATOR.

Application filed August 9, 1921. Serial No. 490,838.

This invention relates to means for indicating outside a bank vault or other guarded structure having an automatic time locking, the unelapsed time before the lock will be opened, and thus, through comparisons of readings taken at short intervals of time, also indicating whether the clock which operates the lock is running.

In bank vaults it is customary to have the time clock which controls the vault door inside the vault, the clock being set before the vault is closed to unlock the door at the desired time. With this arrangement there is no way of knowing, after the vault door has been closed, whether the clock has been properly set or whether the clock is running. Such mechanisms frequently fail to automatically unlock the vault at the desired time. Sometimes this is due to the fact that the clock has stopped. If it can be ascertained that the clock has stopped there are ways of starting the clock from the outside of the vault, but heretofore it has been necessary to drill the door before the cause of the failure of the mechanism to work could be discovered.

The principal objects of the present invention are to determine whether or not the clock has been properly set after the vault is closed, to indicate at all times the progress of the clock and how long it will be until the vault is unlocked, and to indicate whether the clock has stopped in case the vault is not automatically unlocked at the intended time. By knowing the time at which the vault will be unlocked, attempts of an employee in charge of the vault to gain unauthorized access to the same by setting the clock to open in the night-time or on a holiday can be frustrated.

The invention consists in providing means in combination with a clock for indicating outside the vault the progress of the clock. The connection between the outside indicator and the clock is preferably electric, rather than mechanical or pneumatic, inasmuch as the connection can then be established through contacts on the door and casing or through staggered openings on the vault. Instead of continuously indicating the progress of the clock, the indicator may operate intermittently to indicate the advance of the clock, by steps of one hour for example. In the preferred form the inven-

tion comprises a resistance element controlled by the clock which in turn controls an electric indicator outside the vault, the indicator being calibrated preferably in terms of hours. The features of the invention are clearly shown in the drawings in which,

Fig. 1 is a front elevation of a time-clock;

Fig. 2 is a side elevation of the same;

Fig. 3 is a sectional view on the line 3—3 of Fig. 1;

Fig. 4 is a sectional view of the upper portion of the clock on the line 4—4 of Fig. 2;

Fig. 5 is a diagrammatic showing of the electric circuit;

Fig. 6 is an elevation of a portion of a bank vault showing the general arrangement of the device, parts within the vault being indicated by broken lines;

Fig. 7 is a plan view of the element shown in Fig. 6; and

Fig. 8 is a sectional view on the line 8—8 of Fig. 7.

The particular embodiment of the invention shown for the purpose of illustration is diagrammatically illustrated in Figs. 6 and 7, in which reference character 9 indicates the time-clock within the vault and 10 the indicator upon the exterior, the electric connection between the two being shown by broken line 11.

The time-clock is shown in detail in Figs. 1—4 and consists of upper and lower spaced plates 12 and 13 housing therebetween the usual clock gearing A driven by main spring B, and provided with escapement assembly C. Upon the front face of plate 12 is a rotatable dial 14 calibrated in hour spaces, and provided on its periphery with gear teeth which mesh with gear teeth upon a pinion 15, mounted on shaft 16 which has a squared projecting end 17 over which the winding and setting key is adapted to fit. The main spring B is attached to shaft 16 by which it is adapted to be wound. Shaft 16 serves as the winding means for the main spring B as well as the setting and driving means for the dial 14. Upon the upper face of dial 14 is a pin 18 which operates the lock of the vault. Attached to the upper plate 12 of the time-clock and overhanging dial 14 is a fixed pointer 19 in relation to which the setting of the dial is made. Im-

mediately behind dial 14 and attached to plate 12 is a circular resistance coil 20 which consists preferably of a winding of resistance wire about an insulated core, the same being separated by insulation from the plate 12. The turns of the resistance wire upon the side adjacent the dial 14 are exposed and arranged to be contacted by a finger or contact member 21, fast upon the back of dial 14.

In Fig. 5 is shown the electric circuit which connects the indicator 10 upon the exterior of the vault with the resistance coil upon the clock within the vault. The circuit runs from ground to resistance 27, thence to the battery 22, thence to the indicator 10, thence to the switch 23, thence to the resistance winding 20, thence to the finger 21 and thence back to the ground.

In order that the walls of the vault may not be weakened by drilling the same to make the connections from the clock to the indicator and in order that the device may operate only when the bank vault is closed, the preferred connection is by way of the door casing and the door, the same being shown in Figs. 6 to 8. Since the current in the circuit will be of low amperage and voltage only a small wire is needed which may be led in a shallow groove in the walls of the vault following the surface of the stepped contour of the door casing and the door, the connection being made at 24 on Fig. 7 by means of contacts 25 and 26 upon the casing and the door respectively. If preferred, an induced current, instead of a direct current could be used to operate the indicator.

The operation of the device is as follows: The dial of the clock 14 being set relative to pointer 19 to indicate the number of hours to elapse before the vault will be automatically opened, the finger 21 will contact with a certain portion of the resistance winding 20. Upon the closing of the vault door the connection in the electric circuit of the indicator is made and a current flows through the latter and is indicated by the pointer of the indicator or electric meter 10. As the dial revolves more and more of the resistance of the winding is cut out and the indicator

finger of the armature 10 moves to the right, marking off the passage of the hours at exactly the same rate as the dial. When the time is reached at which the lock is to be sprung through the action of pin 18, the indicator will have reached the extreme position at the right with the full current of the battery 22 flowing.

I claim:

1. Vault protection apparatus comprising lock control mechanism located inside the vault and inaccessible from the exterior thereof when the vault is locked, said mechanism including means adapted to be set so that the vault lock will be conditioned for opening at the end of a period of time of determined length, and being designed to prevent the unlocking of the door until the expiration of said period, and an indicator outside of the vault for indicating the unelapsed portion of said period, and means whereby said indicator is electrically controlled by said mechanism to show the unelapsed portion of said period, whereby the condition of the lock control mechanism is indicated exteriorly of the vault during the time in which it is inaccessible.

2. Vault protection apparatus comprising locking mechanism located within the vault and inaccessible from the exterior thereof when the vault is locked, said mechanism including time controlled means adapted to be set to prevent manipulation of the locking mechanism before the termination of a period of time of determinable length, an element of said time controlled means being movable in accordance with the unelapsed portion of said period, an indicator outside of the vault for showing the unelapsed portion of said period, and energy transmitting means for permitting said element to control the position of said indicator, said energy transmitting means being arranged to prevent tampering with the indicator or with the portion of the means outside the vault from affecting the condition of the locking mechanism.

Signed by me at Boston, Massachusetts, this 3rd day of August, 1921.

FRANKLIN E. CRAWFORD.
